UNITED STATES PATENT OFFICE

160,703

MICROSCOPE

Bernhardt G. Gallasch, Rochester, N. Y., assignor
to Bausch & Lomb Optical Company, Rochester,
N. Y., a corporation of New York

Application September 23, 1948, Serial No. 148,735

Term of patent 14 years

(Cl. D57—1)

To all whom it may concern:

Be it known that I, Bernhardt G. Gallasch, a citizen of the United States and a resident of Rochester, county of Monroe, and State of New York, have invented a new, original and ornamental Design for a Microscope, of which the following is a specification, reference being had to the accompanying drawing, forming a part hereof.

Fig. 1 is a perspective view of a microscope embodying my new design.

Fig. 2 is a side elevational view, on an enlarged scale, of the lens bracket of the microscope.

Fig. 3 is a front elevational view of the lens bracket.

The characteristic features of the design are shown in full lines on the drawing.

I claim:

The ornamental design for a microscope, substantially as shown and described.

BERNHARDT G. GALLASCH.
